UNITED STATES PATENT OFFICE.

EUGENE HEIM AND CELESTIN MATZ, OF CINCINNATI, OHIO.

FINGER-NAIL TRIMMER.

SPECIFICATION forming part of Letters Patent No. 244,891, dated July 26, 1881.

Application filed June 9, 1881. (No model.)

To all whom it may concern:

Be it known that we, EUGENE HEIM and CELESTIN MATZ, both of Cincinnati, Hamilton county, Ohio, have jointly invented a new and 5 useful Finger-Nail Trimmer, of which the following is a specification.

Our device consists, essentially, of a pair of nipping-jaws composed of a single plate of spring-steel so formed and bent as to bring 10 its cutting-edges in opposition and nearly in contact, and in association with this a means for closing said edges together, in which a yoke secured to one jaw affords pivot-bearing for a cam-headed lever, whose operation presses 15 the jaws forcibly together. This lever is preferably of flattened form, and is roughened on its rear surface to serve as a rasp, and from its free extremity projects a hook which serves as a glove-buttoning device. A small catch enables 20 the user to lock the parts into compact form for the pocket, and a bow or bail enables suspension of the instrument from a belt or watch-chain.

In the accompanying drawings, Figure 1 is 25 a perspective view of our device in its folded condition. Fig. 2 is a section of the device in the plane of action. Fig. 3 is a top view of our device with the cam-lever thrown back.

A represents a piece of plate-steel, which, 30 having the represented inturned and curving cutting-edges *a a'* formed upon it, is bent to a **U** form, so as to constitute a pair of nipping-jaws, which stand normally some distance asunder, but which are capable of being pressed 35 toward one another so as to bring their cutting or nipping edges in contact. In order to enable this closure of said jaws to be effected with sufficient ease and power, we attach to one jaw a yoke, B, whose perforated cheeks *b b'* receive 40 the pivot *c* of a cam-headed lever, C, whose depression, as indicated by arrow in Fig. 2, operates to force the jaws closer together until

they meet, as shown in Fig. 1. On release of lever-pressure, as above, the resilience of the jaws causes their automatic separation, so as 45 to facilitate another effective action.

A portion of the rear surface of the cam-lever C may be grooved or roughened, *c'*, to constitute a file or rasp.

Pivoted at D to the bend of the jaws is a 50 catch or clasp, E, whose hook, being forced to occupy a depression, *c''*, in the cam-lever, serves to hold the latter to the closed condition. The same pivot D also serves to couple 55 to the instrument a bow or bail, F, by which the instrument may be suspended from a watch-chain or other object.

The free extremity of the cam-lever may possess the form of a hook, G, suitable for buttoning gloves. 60

We are aware that finger-nail trimmers have been devised with two hinged jaws held normally gaping by a spring, and having separately-attached nipping-edges, the jaws being compressed by the direct pressure of the operator's thumb and finger, and we therefore disclaim invention, broadly; but 65

We claim as new and of our invention—

1. A pair of nail-clipping jaws, *a a'*, formed of a single integral piece of steel, A, which 70 jaws are held normally gaping by their resilience, and are closed by a cam-headed lever, C, substantially as set forth.

2. The finger-nail trimmer consisting of **U**-formed plate A, yoke B, cam-headed lever C, 75 and clasp E.

In testimony of which invention we hereunto set our hands.

EUGENE HEIM.
CELESTIN MATZ.
